UNITED STATES PATENT OFFICE.

JOHN H. HERTNER, OF CLEVELAND, OHIO, ASSIGNEE TO THE BAKER-RAULANG COMPANY, OF CLEVELAND, OHIO, A CORPORATION OF OHIO.

TRUCK.

Original application filed September 10, 1919, Serial No. 322,835. Divided and this application filed June 16, 1924. Serial No. 720,295.

This invention relates to an industrial truck having embodied in it a load handling member, for example, a vertically movable platform; more particularly the invention 5 has to do with the control means for the elevating mechanism of the truck.

This application is a division of my application filed September 10, 1919, Serial No. 322,835, Patent No. 1,505,889, dated Aug. 10 19, 1924.

One object of the invention is to provide an improved control means having associated with it a mechanism for automatically stopping the movement of the load handling 15 member at a predetermined position.

Another object of the invention is to provide a relative simple mechanism for automatically stopping the movement of the load handling member at a predetermined position. 20

Another object of the invention is to provide an improved truck wherein its control mechanism is returned to neutral position when the load handling member moves to its 25 extreme position.

Other objects of the invention will be apparent to those skilled in the art to which my invention relates from the following description taken in connection with the accompanying drawings, wherein 30

Fig. 1 is a side elevation of a truck embodying my invention, parts being broken away.

Fig. 2 is a fragmentary plan view, with a 35 portion of the platform or vertically movable member, broken away on a central longitudinal line.

Fig. 2^a is a plan view of the platform moving mechanism, parts being broken 40 away.

Fig. 3 is a view of the lever mechanism and controller for operating the elevating motor.

Figs. 4, 5 and 6 are fragmentary views of 45 the motor operating mechanism showing the operation thereof.

Fig. 7 is a top plan view of the parts shown in Fig. 3, parts being broken away.

Fig. 8 is a sectional view on the line 8—8 50 of Fig. 3.

Fig. 9 is a section on the line 9—9 of Fig. 3.

Fig. 10 is a section on the line 10—10 of Figs. 7 and 9.

Fig. 11 is a section on the line 11—11 of 55 Fig. 10.

Fig. 12 is a section on the line 12—12 of Figs. 7 and 9.

In the drawings, 1 indicates as an entirety the frame of the truck. The truck frame 60 may comprise a relatively low section 1^a and an elevated section 1^b connected by brackets 1^c, in any well known manner, for example, by rivets, to form a rigid frame, the elevated section serving to support the necessary storage batteries 2 and a traction motor 3. 65

Near its opposite ends, the low section 1^a is provided with inclines 4, the purpose of which will be later set forth. The traction 70 wheels 6 are mounted on spindles which are connected to the adjacent axle (not shown) by suitable knuckles, whereby they may be used for steering purposes. The knuckles and axle are preferably constructed to receive and support driven axle sections, which are connected by universal joints with the wheel spindles to drive the latter. 75

7 indicates a pair of relatively small supporting wheels mounted below the low portion of the truck frame 1. The wheels 7 80 may be of any desired form of construction, and preferably mounted to swing for steering purposes.

10 indicates a platform on which the operative stands. The pedal 11 is connected to and operates upon the brake (not shown) which acts upon the traction motor 3 or an element driven thereby. The brake is spring operated and the connections are so arranged 85 that downward pressure on the pedal 11 will release the brake, which condition will continue until the pressure on the pedal is released. 90

12 indicates a controller through which 95 the electric circuit from the batteries 2 is completed to operate the motor 3 in either direction. 13 is a suitable handle having a trigger mechanism 13^a, for operating the controller 12. 100

The traction and supporting wheels 6 and 7 are preferably connected together, one element of these connections being indicated at 15, whereby they may be steered simulta-

neously by a handle 14^a connected to a steer-connected to the lever 45 and arranged to move it in a direction to release the brake elements 44^a, 44^b, by a control mechanism 49 presently to be described.

25 indicates as an entirety the load handling member which is herein shown as a vertically movable platform for the truck, having depending side walls 25^a. 26 indicates a pair of channel bars, arranged near the opposite ends of the platform 25 and extending transversely thereof (only one being shown). At its opposite ends each bar 26, is provided with depending arms 26^b. 27 indicates a stud shaft carried by each depending arm and arranged to loosely support a roller 28 which engages with the adjacent incline 4. The rollers 28 are preferably flanged so as to guide the platform and prevent lateral movement thereof at all times. The lowermost or normal position 20 of the platform 25 is shown in Figs. 1, 2, 3, and 4, but movement of the platform longitudinally inwardly or in a direction toward the operative's platform 10, will, through the co-action of the rollers 28 and inclines 4, elevate it to the position shown in Fig. 6; likewise, operation of the platform in the opposite direction will cause it to be lowered to normal position. 29 indicates as an entirety the mechanism for moving the platform interposed between it and the frame 1, and suitably supported on the latter, a portion only of this mechanism being shown in dotted lines in Fig. 7. As disclosed in the aforesaid patent, this mechanism comprises 35 a motor 29^a, and a screw and nut—one of the latter elements being operated by the motor 29^a to act on the other element and effect movement of the platform 25. The motor 29^a is driven in either direction to 40 effect raising and lowering of the platform 25.

44 indicates a brake mechanism for one of the driven elements of the platform operating mechanism 29. The brake mechanism 45 is preferably applied to that shaft directly operated by the motor 29^a. 45 indicates a lever mounted on a bracket 46 fixed to the casing for the moving mechanism 29. 44^c indicates a rod pivoted at one end to the lever 45 and connected, preferably adjustably, with the brake element 44^b, whereby movement of the lever 45 inwardly will press the brake element 44^b against the other brake element 44^a and stop the shaft 30^c.

55 The connection between the outer end of the rod 44^c and lever 45 is preferably of the slideable pivotal type whereby it will accommodate itself to the movement of the lever 45 as the lever swings about its pivot.

60 47 indicates a spring, one end of which is fixed to the adjacent frame section 1^a. The opposite end of the spring 47 is connected to the lever 45 and acts at all times to move the lever in the direction to press the brake elements together. 48 is a rod pivotally

70 Of the motor operating or control mechanism 49, 50 indicates a controller the shaft 50^a of which is movable in opposite directions to complete the circuits to cause rotation of the motor armature shaft in one direction or the other. The controller shaft 75 50^a carries a pair of cams 52, 52^a, the purpose of which will be later set forth. The controller 50 is preferably enclosed within a casing 53 which may be formed of two box sections 53^a, secured together in any desired manner. 54 indicates an arm fixed to the shaft 50^a. The arm 54 may comprise one arm of a bell crank lever. The other arm 54' of the lever will be later referred to. 55 80 54 indicates connections leading from the arm 85 54 to a handle 56 by means of which the connections 55 and through them the controller shaft 50^a is operated. The handle 56 and the elements constituting the connections 55 are preferably mounted upon the frame work 90 of the vehicle, as clearly shown in Fig. 3.

57 indicates a rock shaft mounted in suitable bearings carried by a side wall of one of the box sections 53^a (see Fig. 11). At its inner end the shaft has fixed to it a lever 95 57^a adapted to engage with the cams 52, 52^a. When the shaft 50^a is in neutral position, the engaging end of the arm or lever 57^a is disposed between the cams 52, 52^a (see Fig. 12) in position to engage either one of them accordingly as the shaft 50^a is moved in one direction or the other (see Figs. 4, 5 and 6). The cams 52, 52^a, are so arranged that upon the operation of the shaft 50^a in either direction one of them will swing the lever 57^a 100 and thus cause the shaft 57 to rock. The outer end of the lever 57^a is preferably provided with an anti-friction roller 58 which rolls on the cam surfaces. At its outer end each cam is provided with a notch 52' to receive the roller 58. The engagement of the roller 58 with the notch 52' not only holds the lever 57^a in operated position, but also prevents movement of the controller under the influence of the spring 47 back to its normal position. At its outer end the shaft 57 carries a lever 59 to which is connected a rod 60. 61 indicates a bell crank lever 110 pivotally mounted on the adjacent frame member. One arm of the lever 61 is pivotally connected to the opposite end of the rod 60; the other arm of the lever 61 is pivotally connected to the forward end of the rod 48. From the foregoing description it will be seen that when the controller 50 is operated by movement of the handle 56, to drive the elevating motor 29^a, one of the cams 52, 52^a, through the lever 57^a and connections 59, 60 and 61, pushes the rod 48 rearwardly, the effect of which is to re- 120 125 130

lease the brake 44. By operating the handle 56 in the opposite direction with sufficient force to overcome the resistance due to the engagement of the roller 58 with the walls 5 of the adjacent notch 52', the current may be cut off and the motor stopped. Simultaneously the arm 57^a will assume its normal position (see Figs. 3, 5 and 12), allowing the brake 44 to operate under the influence of 10 the spring 47. The elements just referred to are preferably so arranged and correlated that the spring 47 will not only reset the brake 44, but will also transmit its power through the rod 48, lever 61, rod 60, arm 59 15 and shaft 57 to the arm 57^a; whereby the latter acting upon one of the cams 52, 52^a, will move the controller shaft 50^a, back to its neutral position whenever sufficient movement of the shaft 50^a takes place to move 20 the roller out of the adjacent notch 52' and over the wall thereof.

I prefer to provide between the controller shaft 50^a and the platform 25 means (indicated as an entirety at 62) which automatically release the controller 50, upon the platform reaching either its extreme upper or lower position.

Of these release means 62, 62^a indicates a rock shaft mounted in suitable bearings carried by one of the frame member (see Fig. 8). At its inner end the shaft 62^a carries an arm 63 to the free end of which is pivotally connected a rod 64. The rear end of the rod 64 is pivotally connected in any well known manner to the forward end of the platform 25, preferably the adjacent bar 26 thereof. By this construction and arrangement it will be seen that the platform 25, will, through the rod 64, and arm 63 rock the shaft 62^a, as it moves upwardly and downwardly. At its outer end the rock shaft 62^a carries a plate 65 on which are mounted a pair of spaced tappets 66, 66^a. The plate 65 is fixed to the shaft 62^a in any desired way. 67 indicates a rod pivotally connected to the arm 54' at one end and at its opposite end to a lever 68 loosely mounted on the shaft 62^a (see Figs. 8 and 9). 69 indicates a lug carried by the lever 50 68 and arranged in the path of movement of the tappets 66, 66^a. Accordingly, as the plate 65 moves about the axis of the shaft 62^a, one of the tappets, 66, 66^a, will engage with the lug 69 and move the arm 68, which in turn through the rod 67 and arm 54' will move the controller shaft 50^a toward its neutral position. The tappet is so arranged that it will move the arm 68 and the elements connected thereto far enough to release the roller 58 from the adjacent notch 52', whereupon the arm 57^a, through its engagement with the adjacent cam, and acting under the influence of the spring 47, will complete the movement of the shaft 50^a to 60 neutral position. The plate 65 is prefer-

ably provided with two arc-shaped slots 65^a which permit adjustment of each of the tappets 66, 66^a, angularly about the axis of the shaft 62^a. By means of such adjustment, release of the controller shaft 50^a and the 70 subsequent cutting off of the current can be effected at any desired point in the movement upwardly or downwardly of the platform 25. To permit of ready adjustment, each of the tappets 66, 66^a, may consist of 75 a bolt 66' extending through the adjacent slot 65^a and carrying on its outer end a nut to clamp the bolt head against the plate 65. When this construction is employed, the head of the bolt 66' may serve as a tappet to 80 engage the lug 69.

A brief description of the operation of the release mechanism 62 will make its construction clear. Assuming that the elements are at rest and the platform 25 is in its lowermost position, operation of the handle 56 will move the arms 54, 54' and shaft 50^a in a clockwise direction (see arrow in Fig. 4) and position the lug 69 substantially midway between the tappets 66, 66^a. The circuit to the motor 29^a having been closed the motor will be operated and the platform 25 raised to the position shown in Fig. 5. The movement of the platform 25, through the rod 64, arm 63, and shaft 62^a, will swing 90 the plate 65 about the axis of the shaft 62^a. As the platform approaches the limit of its movement, the tappet 66^a will engage the lug 69 and through it move the arm 68 sufficiently to disengage the roller from the 100 notch 52' and hence release the controller shaft 50^a in the manner already described, and permit the latter to be returned to neutral position under the action of the spring 47. If now it is desired to lower the platform 25, the handle 56 is operated in the opposite direction to move the controller shaft 50^a to the position shown in Fig. 6. This operation will position the lug 69 substantially midway between the tappets 66, 110 66^a, so that as the platform 25 moves downwardly, the plate 65 will be moved in the opposite direction and cause engagement of the tappet 66 with the lug 69.

It will thus be seen that when the elevating motor 29^a is set in operation for raising and lowering the platform, the release means 62 will automatically stop or shut off the current to the motor at the proper time as the platform moves to its extreme position in either direction. This construction not only prevents any damage occurring to the apparatus but it saves time, relieves the operative of care and responsibility and lessens the wear on the elevating motor and 120 other elements of the apparatus.

To those skilled in the art to which this invention relates many alterations in construction and widely differing embodiments and applications of my invention will sug- 125

gest themselves without departing from the spirit and scope thereof. My disclosures and description herein are purely illustrative and are not intended to be in any sense limiting.

What I claim is:—

1. In apparatus of the class described, the combination with a frame, an elevating member mounted to move in opposite directions thereon and means including a motor and a controller for operating said member in either direction, of a brake for said motor normally applied to an element driven by said motor, cams arranged to be actuated by said controller, a device acted upon by said cams and operatively connected to said brake for releasing the latter when said controller is operated, a rotatable device connected to and operated by said member and carrying spaced tappets, an arm mounted to swing relative to said rotatable device about its axis, and a connection between the controller and said arm, whereby the latter is moved into operative relation to one of said tappets when said controller is operated.

2. An apparatus as claimed in claim 1 in which each of the said cams is provided with a notch to receive said cam actuated device and coacts therewith to lock the brake and controller in their operated positions.

3. An apparatus as claimed in claim 1 in which said tappets are independently adjustable about the axis of said rotatable device.

4. In apparatus of the class described, the combination with a frame, an elevating member mounted to move in opposite directions thereon and means including a motor and a controller for operating said member in either direction, of a brake arranged to act on an element driven by said motor to stop it, connections between said brake and said controller normally tending to apply said brake and return said controller to neutral position, said connections including interlocking devices serving to lock the said brake and controller in operated positions, irrespective of the position of said member, and means actuated by said member and connected to said controller for releasing said interlocking devices when said member moves in either direction to a predetermined position.

5. An apparatus as claimed in claim 4 in which the means actuated by said member comprise a rotatable device operated by said member and an arm connected to said controller and operated thereby into operative relation to said rotatable device.

In testimony whereof, I have hereunto subscribed my name.

JOHN H. HERTNER.
